MATERIAL-BREAKING APPARATUS

Louis A. Maxson, Claremont, N. H., assignor, by
mesne assignments, to Safety Mining Company,
Chicago, Ill., a corporation of Illinois

Application April 27, 1935, Serial No. 18,641
Renewed July 30, 1936

17 Claims. (Cl. 102—6)

My invention relates to apparatus for the breaking down of coal and other materials by the release from suitably positioned containers of relatively large charges of a highly compressed gaseous medium, and more particularly to improvements in devices of the so-called pre-charged variety for that purpose.

In the breaking down of coal and other materials, and for similar operations, it has been found practicable and highly advantageous to employ charges of highly compressed gaseous media instead of explosives. There are two general methods of this. One involves the lodging of an uncharged "shell" or container in a suitably formed hole in the material to be fractured, and then forcing into the container a charge of highly compressed gaseous medium, and thereafter, in an appropriate manner and in the same sequence of operations, effecting a release of the stored charge and the breaking thereby of the material in which the container is lodged. The other method comprises the pre-charging of containers at an appropriate and convenient location, the transportation of these containers to the desired point of use, the preparation of holes to receive them, the setting in operation of an automatic time-delay device for effecting release of the charge, the immediate positioning of the container fully in the position which it should occupy upon release of its charge, and, after the lapse of the predetermined time delay inherent in the operation of the automatic discharging device, release of the charge, the operator having, during the time delay period, retired to a place of safety.

The present invention relates more particularly to this latter type of material-breaking apparatus, and an object of the invention is to provide an improved safety arrangement for precluding even the minutest possibility of unintended release of the charge from a pre-charged container.

Such pre-charged containers of the character hereinabove mentioned comprise a charge release valve held in closed position by the entrapping of a charge of highly compressed medium in a chamber where it acts upon a discharge valve closing plunger of greater effective cross sectional area than the discharge valve; and release of the charge is effected by the venting of the pressure entrapped in the chamber mentioned. Venting is normally effected by the unseating of a check valve which is held in closed, pressure-trapping position, both by a spring and by the pressure of the entrapped medium. Such valves have been known to remain leak-proof for many weeks, but in the interest of safety the provision of an addi-

tional assurance against unintended discharge, which might occur were the check valve to be unseated accidentally, or to leak, is desirable.

From one of its aspects, my invention comprises the provision of a valve which positively interrupts communication between the control chamber and the check valve at all times except when such communication is desired in order that discharge may be effected. From another aspect, my invention comprises the provision of means for maintaining constantly replenished from the main charge storage space of the shell, the pressure within the control chamber, should there be any leakage at the check valve. From still another aspect, my invention includes a combination of the functions last described, with an interruption of the replenishing circuit, as it were, when discharge is desired; and in different embodiments my invention may comprise wholly manual means for effecting the desired results, or it may comprise an embodiment in which no manual operation is requisite and through a special check valve arrangement complete safety is effected.

It is another object of my invention to provide an improved, safety-type, pre-charged shell. It is a further object of my invention to provide an improved, safety-type, pre-charged shell requiring a deliberate operation on the part of the operator to prepare the shell for release of its charge. It is still another object of my invention to provide an improved pre-charged shell having an improved check valve associated therewith which in closed position insures maintenance of the pressure in the control chamber of the shell, and in its open position interrupts communication between such control chamber and the source of pressure medium supply with which the same communicates when the check valve is closed. Other objects and advantages of the invention will hereinafter more fully appear.

In the accompanying drawing, in which two illustrative embodiments of the invention are shown,—

Fig. 1 is a central longitudinal section through a cartridge or shell in which one illustrative embodiment of the invention is incorporated.

Fig. 2 is an enlarged section through a portion of the outer end of the shell of Fig. 1.

Fig. 3 is a transverse section on a plane corresponding to the line 3—3 of Fig. 2.

Fig. 4 is a fragmentary section corresponding to Fig. 2, showing the "safety" valve in a different position.

Fig. 5 is a view similar to Fig. 2, showing a modification.

Fig. 6 is a transverse section on a plane corresponding to the line 6—6 of Fig. 5.

5 The invention, in both illustrative embodiments, is shown incorporated in a shell which is of the general type disclosed in a co-pending application of one Frank H. Armstrong, Serial No. 718,175, filed March 30, 1934 (see Fig. 12), 10 and this shell is of the type which is designed to be charged at some central charging station and then transported in a precharged condition to the point of use.

The shell comprises an elongated cylindrical 15 container 1 having a chamber 2 for receiving a charge of highly compressed gas. At 3 there is threadedly connected to the "inner" end of the container a discharge cap 4, while a control cap 5 is threadedly connected at 6 at the opposite 20 end of the container 1. The discharge cap 4 comprises a central discharge chamber 7 which communicates through a series of appropriate discharge ports 8 with the exterior of the shell. A conical charge release valve 9 seats upon the 25 inner end of the discharge cap 4. The valve 9 is provided with an axial guide extension 10 which is guided in a bore 11 formed in the discharge cap. The control cap 6 has a bore 12 in which a plunger 13 is reciprocable. A valve rod 30 14 connects the valve 9 and the plunger 13, and extends axially through the pressure chamber 2. A keeper 16, threadedly supported by the rod 14, holds a cup leather 17 against the plunger 13 and precludes leakage of high pressure medium along the control chamber past the plunger to a space 15 at the outer side of the plunger 13. A suitable metallic, axially perforated septum 18 supports a hat leather 19 which cooperates with the exterior of the rod 14 and acts as a check 35 valve to permit the passage of pressure from within the chamber 2 to a space 20 between the plunger and the septum, while precluding reverse flow. The valve rod is axially bored at 21, and the bore 21 communicates, under the control of 40 a spring seated check valve 22, controlling an opening 23 in the plunger 13, with the chamber 15; and at its other end the bore communicates through passages 24 with the chamber 2. A bleed passage 25 of small area is provided at a 45 suitable point to permit leakage out, of the pressure entrapped within the chamber 20, after the charge has been released, in order that the valve 9 may be more readily reseated.

According to the conventional design of 50 discharge caps of the type described, a passage 26 is arranged to connect, upon the opening of a spring-seated check valve 27, the chamber 15 with the exterior of the discharge cap at the outer end of the latter, as at 28.

60 Various means are provided for the effecting of the unseating of the valve 27 when discharge is desired, and I have illustrated a discharge gun which is the invention of one Frank H. Armstrong, above mentioned, for the purpose of 65 showing one type of mechanism which may be used for effecting shell discharge when desired. This gun is designated 30 and comprises a casing 31 threadedly secured, as at 32, to the outer end of the control cap 5. The casing 31 comprises 70 a cylinder bore 33 coaxial with the shell and containing a reciprocable piston 34. A water-containing chamber 35 is arranged at the outer end of the gun casing, and a passage 36, controlled by a normally closed needle valve 37, is 75 adapted, when the needle valve is opened, to

conduct water into the space to the outside of the plunger 34. The plunger 34 is normally maintained in its retracted position (that shown in Fig. 1) by a spring 38, and carries a cage 39 containing calcium carbide. Obviously, when the shell is horizontal, a material amount of water must flow from the storage chamber 35 into the space to the outside of the plunger 34 before the water will reach the carbide in the cage 39. Accordingly, a definite time delay may 10 be assured after the valve 37 is opened, by properly proportioning the passage 36 and the volume of the space to which the water is admitted in order that it may act upon the carbide. One or 15 more radial discharge passages 40 extend from the space 41, which is formed between the forward end of the gun and the outer end of the control cap; and upon the generation of pressure sufficient to move the plunger 34 to unseat, 20 through its operating stem 42, the check valve 27, the pressure within the chamber 15 will be released through passage 26, past valve 27, through passage 28, space 41, and port means 40, to vent the chamber 15 and permit the pressure in the space 20 to move the valve 9 to 25 charge releasing position, and there hold it.

The mode of operation of the device will be clear from what has just been said, but it may be worth while to state that when it is desired to release the charge from a shell or container 1, a head 39 will be applied to it; the shell or container will be placed in the hole which it is to occupy when the charge is released; it will be brought into a position where the passage 36 is 30 at the bottom; the valve 37 will be opened; the shell will be shoved home in its hole; a suitable quick-tamping may be thrust into the hole outside the container, if desired; and the operator will retire to a safe position; and, after a predetermined time, determined by the proportioning 35 and design of the parts, perhaps one or two minutes, the water will attain sufficient contact with the carbide to generate pressure enough to unseat the valve 27, vent the space 15, and cause 40 release of the charge.

Now, as pointed out above, while shells of this character will maintain the pressure in the space 15 for long periods, it would be safer to prevent completely any possibility of premature discharge due to release or leakage out of the pressure within this chamber; and in the embodiment shown in Figs. 1 to 4 inclusive, I provide a manually rotatable plug valve 45 in a bore 46 which intersects the passage 26, and provide in this plug valve a through passage 47 which, when aligned with the 50 passage 26, permits flow outwardly from the chamber 15 through the passage 26 to the check valve 27, and past the latter, if the latter be opened, to atmosphere. The valve 45 is suitably packed at its opposite ends, as indicated at 49 and 50, and has a polygonal socket 51 in its larger end, with which a wrench may cooperate in moving the valve between its opposite positions. A passage 52 extends from the chamber 15 into communication with the bore 46 at a point at right angles to the communication with the latter of the passage 26, and a passage 53 having communication with the bore 46 in alignment with the passage 52, extends forwardly to any suitable point whence 55 pressure may be conducted to the chamber 15, either to the chamber 2 directly or, more simply and equally satisfactorily, to the space 28. When the valve 45 is in the position shown in Fig. 4, 60 passages 52 and 53 are connected so that the same 65 pressure will prevail in chamber 15 that prevails 70 in the space 28. When the valve 45 is rotated so that the passage 52 is aligned with the bore 46, the pressure in the space 28 will be relieved, and the pressure in the space 20 will prevail in the chamber 15, 75 so that the valve 9 will be held in its charge-releasing position.

in chamber 20, and therefore the valve 9 will be positively maintained closed. At the same time, the passage 26 is cut off from communication with the valve 27 and discharge orifice 28, and the cartridge is doubly secured against accidental discharge. This is the position of the valve 45 used during transportation of the cartridge, and the valve is maintained in this position until just prior to the time when discharge is desired.

When it is desired to discharge the cartridge within a moment or two, the valve 45 will be turned to the position shown in Figs. 1 and 2, and this will interrupt communication between passage 53 and passage 52 and prevent any escape of pressure from the space 20, and will open communication between the space 15 and the check valve 27. It will be evident that double assurance against premature discharge is provided by this device, and that the operator must deliberately turn the valve 45 to discharging position in order that the shell may be discharged.

In the species of the invention shown in Figs. 5 and 6, the need for a manual operation in order to permit discharge, is dispensed with, but the possibility of lowering of the pressure within the chamber 15 through leakage is avoided by provision for continuous maintenance of the same pressure in that chamber as in the space 20. The passage 53' corresponds, in this form of the invention, with the passage 53 of the first species. The passage 52' corresponds with the passage 52 of the first species. However, instead of using a mere ball check, a plunger type check valve is provided at 60, and this plunger type check valve has a peripheral groove 61 which connects the passages 52' and 53' when the forward conical portion 62 of the valve device 60 is seated. A spring 63 maintains the valve device 60 normally in seated position. The valve device 60 is reciprocable in a chamber 64 and has a forward surface 65 partially counterbalancing the pressure upon the rear end of the valve. Bypass passages 66 extend outside the chamber 64 and connect the front and rear ends thereof, so that on unseating of the conical portion 62 the pressure may pass freely past the valve device from the chamber 15 outwardly. It will be obvious that in this form of the invention the replenishment feature is present; and that loss of pressure from chamber 20 upon release of the charge by unseating the valve 60 is precluded because the groove 61 will not connect the passages 52' and 53' when the valve device 60 is moved from its seat by the operating stem 42. However, the feature of a double guard is not provided in this form of the invention. The shell charging opening is shown in several figures at 70.

From the foregoing description, it will be evident that I have provided an improved apparatus for the safe breaking down of coal and other materials; that in each of its embodiments illustrated, premature discharge due to reduction of pressure in the control chamber is prevented, and that in one of its embodiments this is prevented not only by assuring maintenance of like pressure conditions in that chamber and in the space where pressure acts to effect opening of the discharge valve, but also venting of the control space is positively precluded. It will be obvious that in both forms the device is simple, that it is fool-proof, and that additional assurance against possible premature discharge may be furnished in different degrees, as may be desired by the user of the shells.

While I have in this application specifically described two embodiments which my invention may assume in practice, it will be understood that these are shown for illustrative purposes only and that the invention may be further modified and embodied in various other forms without departing from its spirit or the scope of the appended claims.

What I claim as new and desire to secure by Letters Patent is:

1. In combination, a container for a charge of highly compressed gaseous medium having a charge release valve and means for controlling the position of said charge release valve including an area effective when subjected to charge pressure to maintain the charge release valve closed, and means effective on release of pressure from said area to open the charge release valve, and means including a vent passage and controlling means therefor for releasing pressure from said area when charge release is desired, and means for selectively interrupting communication between the ends of said vent passage and subjecting said area continuously to charge pressure and opening such communication and cutting off said area from charge pressure supply.

2. In combination, a container for a charge of highly compressed gaseous medium having a charge release valve and means for controlling the position of said charge release valve including an area effective when subjected to charge pressure to maintain the charge release valve closed, and means effective on release of pressure from said area to open the charge release valve, and means including a vent passage and controlling means therefor for releasing pressure from said area when charge release is desired, and means including a valve intersecting said vent passage for selectively interrupting communication between the ends of said vent passage and subjecting said area continuously to charge pressure and opening such communication and cutting off said area from charge pressure supply.

3. In combination, a container for a charge of highly compressed gaseous medium having a charge release valve and means for controlling the position of said charge release valve including an area effective when subjected to charge pressure to maintain the charge release valve closed, and means effective on release of pressure from said area to open the charge release valve, and means including a vent passage and controlling means therefor for releasing pressure from said area when charge release is desired, and means including a valve intersecting said vent passage and having but a single flow passage therethrough for selectively interrupting communication between the ends of said vent passage and subjecting said area continuously to charge pressure and opening such communication and cutting off said area from charge pressure supply.

4. In combination, a container for a charge of highly compressed gaseous medium having a charge release valve and means for controlling the position of said charge release valve including opposing areas, one effective on release of pressure from the other to open the charge release valve, and the other effective when subjected to pressure to maintain the charge release valve closed irrespective of pressure on the first, and means including a vent passage and a valve device for venting the pressure on the second mentioned area when charge release is desired, and safety means for precluding acci-

- dental charge release including a manually operable valve in one position closing the vent passage completely.
5. In combination, a container for a charge of highly compressed gaseous medium having a charge release valve and means for controlling the position of said charge release valve including opposing areas, one effective on release of pressure from the other to open the charge release valve, and the other effective when subjected to pressure to maintain the charge release valve closed irrespective of pressure on the first, and means including a vent passage and a valve device for venting the pressure on the second mentioned area when charge release is desired, and safety means for precluding accidental charge release including a manually operable valve in one position closing the vent passage completely and opening communication between said areas.
6. In combination, a container for a charge of highly compressed gaseous medium having a charge release valve and means for controlling the position of said charge release valve including opposing areas, one effective on release of pressure from the other to open the charge release valve, and the other effective when subjected to pressure to maintain the charge release valve closed irrespective of pressure on the first, and means including a vent passage for venting the pressure on the second mentioned area when charge release is desired, and safety means for precluding accidental charge release including a valve having a passage and in one position closing said vent passage and opening communication through its passage between said areas and in another position opening communication through said passage between portions of said vent passage.
7. In combination, a container for a charge of highly compressed gaseous medium having a charge release valve and means for controlling the latter including an area effective when subjected to pressure to maintain the charge release valve closed and an area operative on venting of said first mentioned area to open the charge release valve, venting means for the first mentioned area, and means operative while said venting means is closed to connect said areas in communication with each other.
8. In combination, a container for a charge of highly compressed gaseous medium having a charge release valve and means for controlling the latter including an area effective when subjected to pressure to maintain the charge release valve closed and an area operative on venting of said first mentioned area to open the charge release valve, venting means for the first mentioned area, and a valve operative in different positions to close said vent passage and effect connection of said areas in communication with each other and to open said vent passage and interrupt communication between said areas.
9. In combination, a container for a charge of highly compressed gaseous medium having a charge release valve and means for controlling the latter including an area effective when subjected to pressure to maintain the charge release valve closed and an area operative on venting of said first mentioned area to open the charge release valve, venting means for the first mentioned area, and a reciprocable check valve operative in different positions to close said vent passage and effect connection of
- said areas in communication with each other and to open said vent passage and interrupt communication between said areas.
10. In combination, a container for a charge of highly compressed gaseous medium having a charge release valve and means for controlling the latter including an area effective when subjected to pressure to maintain the charge release valve closed and an area operative on venting of said first mentioned area to open the charge release valve, venting means for the first mentioned area, and a rotary valve operative in different positions to close said vent passage and effect connection of said areas in communication with each other and to discontinue its closure of said vent passage and interrupt communication between said areas.
11. In combination, a container for receiving a high pressure charge and having a charge release valve, differential fluid pressure means operable to hold said valve closed and to open said valve to effect release of the charge, means operable to effect the differential fluid pressure condition which causes opening of said valve, and means for assuring a fluid pressure condition which will hold said valve closed until opening of the valve is desired.
12. In combination, a container having a charge of material breaking medium and charge release means, and means for controlling the latter including an area effective when subjected to pressure to maintain the charge release means closed and an area operative on venting of said first-mentioned area to open the charge release means, venting means for the first-mentioned area, and means operative while said venting means is closed to connect said areas in communication with each other.
13. In combination, a container for receiving a charge of material breaking medium and having a charge release valve and a control chamber, a plunger in said chamber operatively connected to said valve, said plunger being subject to control chamber pressure conditions which either cause the plunger to hold said valve closed or to open said valve, means for establishing the control chamber pressure condition which will cause the plunger to open the valve, and means operative while the aforesaid means is inactive to assure maintenance of the control chamber pressure condition which will cause the plunger to hold the valve closed.
14. In combination, a container for receiving a charge of material breaking medium and having a charge release valve, and a control chamber, a plunger in said chamber operatively connected to said valve, said plunger being subject to control chamber pressure conditions which either cause the plunger to hold said valve closed or to open said valve, means for establishing the control chamber pressure condition which will cause the plunger to open the valve, and manually operable means to prevent operation of the aforementioned means from effecting a control chamber pressure condition which will cause the plunger to hold the valve closed.
15. In combination, a container for receiving a charge of material breaking medium and having a charge release valve and a control chamber, a plunger in said chamber operatively connected to said valve, said plunger being subject to control chamber pressure conditions which either

cause the plunger to hold said valve closed or to open said valve, means for establishing the control chamber pressure condition which will cause the plunger to open the valve, and manually operable means to prevent operation of the aforementioned means from effecting a control chamber pressure condition which will cause the plunger to open the valve.

16. In combination, a container for receiving a charge of material breaking medium and having a charge release valve and a control chamber, a plunger in said chamber operatively connected to said valve, said plunger being subject to control chamber pressure conditions which either 10 cause the plunger to hold said valve closed or to open said valve, means for establishing the control chamber pressure condition which will cause the plunger to open the valve, and means for assuring maintenance of the control chamber 15 pressure condition which will cause the plunger 20

to hold the valve closed, and valve means for controlling operation of both of the aforementioned means.

17. In combination, a container for receiving a charge of material breaking medium and having a charge release valve and a control chamber, a plunger in said chamber operatively connected to said valve, said plunger being subject to control chamber pressure conditions which either cause the plunger to hold said valve closed or to open said valve, means for establishing the control chamber pressure condition which will cause the plunger to open the valve, means for assuring maintenance of the control chamber pressure condition which will cause the plunger to hold the valve closed, and valve means under manual control for permitting operation of only one of said aforementioned means at any one time.

LOUIS A. MAXSON. 20
